(57) **CLAIM**

The ornamental design for an LED high bay light, as shown and described.

DESCRIPTION

FIG. 1 is a perspective view of the LED high bay light showing my new design;
FIG. 2 is a perspective view from another angle thereof;
FIG. 3 is a bottom plan view thereof;
FIG. 4 is a top plan view thereof;
FIG. 5 is a left side elevational view thereof;
FIG. 6 is a right side elevational view thereof;
FIG. 7 is a front elevational view thereof; and,
FIG. 8 is a rear elevational view thereof.
The broken lines shown on the drawings depict portions of the LED high bay light that form no part of the claimed design.
